FOUNTAIN PEN CONTAINER

Filed Feb. 4, 1926

FIG. 1.

FIG. 2.

FIG. 3.

FIG. 4. Invention
Charles J. Funk,
By
Albert Schell
Fetter.

UNITED STATES PATENT OFFICE.

CHARLES J. FUNK, OF CHICAGO, ILLINOIS, ASSIGNOR TO CLARENCE E. BARRETT, DOING BUSINESS AS C. E. BARRETT & CO., OF CHICAGO, ILLINOIS.

FOUNTAIN-PEN CONTAINER.

Application filed February 4, 1926. Serial No. 85,855.

My invention relates to a desk appliance for conveniently storing a fountain pen, and for this purpose aims to provide a substantially airtight compartment in which the 5 pen can be retained without requiring the usual cap to be slipped over the nib end of the pen.

In the ordinary intermittent use of a fountain pen, much time is wasted in shifting 10 the cap from one end of the barrel to the other, since it cannot be left for any considerable time upon the rear end of a pen (when the pen is not in use) without causing ink to dry in the feed of the pen so as 15 to clog the latter. In banks and many departments of commercial establishments, the time thus spent means a waste which should be avoided in the interests of economy, and even in homes many users of fountain pens 20 would prefer to have such pens instantly available for use.

To meet this need, my invention provides a desk appliance including a pen compartment designed for storing a fountain pen in 25 a horizontal position and so constructed as to afford an airtight and dust-tight closure when the lid of the compartment is shut, but permitting the lid to be snapped open when the pen is to be used.

Furthermore, my invention provides an arrangement for this purpose in which the support for the pen is depressed when the lid is closed, thereby permitting the storage compartment to be of relatively low height; 35 and in which the pen-support is automatically raised when the lid is snapped open, so as to facilitate an easy and speedy grasping of the pen. It also provides a pen container for this purpose in which the same 40 spring arrangement serves for raising the pen-support, for swinging the lid to its open position when unlatched, and for insuring a tight seal between the lid and a packing member associated with the body member 45 of the pen container.

Still further and also more detailed objects will appear from the following specification and from the accompanying drawings, in which drawings:

Fig. 1 is a perspective view of an embodi-

ment of my invention comprising a fountain pen container and a pencil rack, showing this as it appears when the lid is open.

Fig. 2 is an enlarged vertical and longitudinal section taken through the same embodiment along the line 2—2 of Fig. 1. 55

Fig. 3 is an enlarged transverse vertical section taken along the line 3—3 of Fig. 1.

Fig. 4 is a fragmentary section similar to the left-hand portion of Fig. 2, taken with 60 the lid in its closure position and with dotted lines showing a portion of a fountain pen stored in the container.

In the illustrated embodiment, my desk appliance has a body member 1 which includes a forwardly extending and relatively low portion provided with upwardly open longitudinal grooves 2 for holding pencils. The rear and taller main portion of the body has an upwardly open chamber 3 of substantially rectangular horizontal section, in which a pen-support is slidably disposed. This pen-support is supported by a pair of compression springs 5 interposed between 65 its bottom and the base 1^A of the body member, and each spring extends into a recess 6 in the bottom of the pen-support so as to prevent the spring from sliding transversely of its axis with respect to the pen-support. 70

A lid 7 is hinged to the body member adjacent to its upper rear edge and desirably on pivot screws 8 disposed forwardly of the said rear edge so that the rear edge of the lid will engage the rear face of the body member for limiting the opening movement 75 of the lid to a position in which the center of gravity of the lid is back of the axes of the pivots, as shown in Fig. 3. Cooperating latch portions are provided on the body member and the lid, such as a forwardly 80 projecting hook 9 on the lid disposed for catching under a rearwardly directed prong 10 on the spring latch 11 secured to the front of the container portion of the body member. 85

When the lid is open, the springs 5 raise the pen support to a position in which both the fountain pen 12 and other portions of the pen-support are above the upper edges 90 of the said chamber, thereby affording ready 95

access to the pen. To facilitate a grasping of the pen, I preferably employ a pen-support consisting of two end portions 4^A and 4^B, each formed after the manner of one end of a trough and adapted jointly to support the fountain pen, and an intermediate portion 4^C connecting these end portions. This intermediate portion preferably has its upper face considerably lower than the pen-supporting troughs, thus leaving the part of the pen between the troughs exposed for convenient reach by the user, as shown in Fig. 4.

I also preferably form portions of the pen-support—such as the trough ends 4^D—so that they will extend above a fountain pen of ordinary diameter and hence will be engaged by the lid during the closing of the latter without having the lid touch the fountain pen. When the lid is being closed, its engagement with these upwardly projecting trough ends causes it to depress the pen-support against the pressure of the springs 5, and when the lid is latched in its closure position, these springs continuously press the pen support up against the lid. Each of the trough ends is preferably convexed upwardly so as to present a curved contact surface to the lid, thereby avoiding a scratching of the latter.

To make the resulting closure airtight, I provide the upper edge of the container with a groove extending entirely around its bore and partly housing a frame-shaped packing member 13 of soft rubber or the like. Then I emboss the lid so as to provide a downwardly directed bead 14 opposite the center line of this packing member. The latter projects beyond the top of the body of the container and hence is engaged by the bead 14 when the lid is forcibly closed, so that the bead indents the packing member (as shown in Fig. 3) and affords a container closure which is both airtight and dust-tight. To prevent the springs from lifting the pen-support to an undue extent, I provide cooperating stop portions on the pen-support and the body member, as for example a screw 15 having its head disposed in the receptacle of the container and disposed for engaging the medial portion 4^C of the pen-support, as shown in Fig. 4.

When stored in my container, the fountain pen is supported in a horizontal position, so that gravity will not feed an excess of ink to the nib of the pen. Hence I avoid the leakage of ink which is objectionable in holders designed for having the downwardly directed forward ends of pens inserted in them. With the latter type of holder, the user is also apt to damage the nib of the pen when hastily inserting the pen in the holder. My container avoids such accidental damage, while always keeping a filled fountain pen ready for instant use.

However, while I have pictured and described my invention in an embodiment which also includes a pencil rack, I do not wish to be limited to such a combination. Neither do I wish to be limited to the use of spring means in the form of two separate springs, nor to other details of the construction and arrangement above disclosed, since many changes might obviously be made without departing either from the spirit of my invention or from the appended claims.

I claim as my invention:

1. A fountain pen container comprising an upwardly open receptacle, a lid hinged to the receptacle; a pen-support disposed within and vertically slidable in the receptacle and having upper portions disposed for directly engaging the lid when the latter is in its closed position, and spring means supporting the pen-support and arranged for pressing the said support against the lid when the latter is closed.

2. A fountain pen container comprising an upwardly open receptacle, a lid hinged adjacent to its rear edge to the receptacle, means for latching the lid in its closed position, a pen-support movable vertically in the receptacle and having upper portions directly engaging the lid when the lid is in its closed position and spring means for supporting the pen-support, the spring means being of such strength as to swing the lid open and out of contact with the pen support when the latching means are released.

3. A fountain pen container as per claim 1, in which the pen-support has its said lid-engaging portions projecting above a fountain pen resting on the support and disposed for preventing the pen from contacting with the lid.

4. A fountain pen container as per claim 1, in which the pen-support comprises a pair of single-ended troughs respectively disposed for supporting the two end portions of a fountain pen, and a medial portion connecting the two troughs and disposed at some distance below the fountain pen.

5. A fountain pen container as per claim 1, in which the pen-support comprises a pair of single-ended troughs respectively disposed for supporting the two end portions of a fountain pen, and a medial portion connecting the two troughs and disposed at some distance below the fountain pen, each trough having its closed end extending above the pen so as to be adapted to engage the lid.

6. A fountain pen container as per claim 1, in which the pen-support comprises a pair of single-ended troughs respectively disposed for supporting the two end portions of a fountain pen, and a medial portion connecting the two troughs and disposed at some distance below the fountain pen, each trough having an end extending above the pen for engagement with the lid, the said end being

upwardly convexed transversely of the trough.

7. A fountain pen container as per claim 1, in which the spring means comprise a

⁵ pair of compression springs spaced longitudinally of the container, the pen-support having its bottom provided with a pair of

recesses respectively entered by and fitting the upper ends of the two springs to prevent a shifting of the springs in any lateral di- ¹⁰ rection.

Signed at Chicago, Illinois, January 30th, 1926.

CHARLES J. FUNK.
